United States Patent Office

Des. 177,901
Patented June 5, 1956

177,901

LIFE JACKET

Willard E. Crotty, Quincy, Mich., assignor to Crotty Corporation

Application May 11, 1955, Serial No. 35,942

Term of patent 14 years

(Cl. D71—1)

Fig. 2

I claim:

The ornamental design for a life jacket, as shown.
